OF PHILADELPHIA, PENNSYLVANIA, ASSIGNEES TO THE DE LUXE BRUSH COM-
PANY, OF WILMINGTON, DELAWARE, A CORPORATION OF DELAWARE.

DEVICE FOR DISPENSING LIQUID OR PLASTIC MATERIALS.

Application filed April 27, 1920. Serial No. 376,924

To all whom it may concern:

Be it known that we, WILLIAM WILSON HEINITSH, ISAAC C. SHALKOP, citizens of the United States, and ALEXANDER B. LAUTERBACH, a citizen of Hungary, and residents of Philadelphia, in the county of Philadelphia and State of Pennsylvania, have invented an Improvement in Devices for Dispensing Liquid or Plastic Materials, of which the following is a specification.

Our invention relates to devices for dispensing semi-liquid, liquid or plastic materials in which the material is contained in a reservoir and in which means is provided for effecting intermittent discharges thereof as desired.

One of the objects of the invention is to provide a simplified construction of such device including means to prevent escape of the material being dispensed into portions of the structure where its presence is not desired or would prove detrimental.

Other objects and advantages of the invention will be pointed out in the detailed description therof which follows or will be apparent from such description.

For the purpose of enabling the invention to be more readily understood and its practical advantages fully appreciated, reference should be had to the accompanying drawing in which we have illustrated one form of a convenient embodiment thereof. However, it will be understood that changes in the details of construction may be made within the scope of the claims without departing from the invention.

As illustrated the invention is embodied in a shaving brush, but it may be employed and applied to and for other purposes and uses.

In the drawing:

Fig. 1 is a central longitudinal section of a device embodying our invention;

Fig. 2 is a transverse sectional view taken on the line 2-2 of Fig. 1; and

Fig. 3 is a central longitudinal sectional view of the rear or upper closed end portion of the handle and the reservoir therein showing the piston in its rearmost or uppermost position.

Referring to the drawing: 1 designates a brush, the upper or inner ends of which are held in the annular space formed between the outer or forward end portions of the

members 2 and 3, the latter being situated 55 inside of the former.

The forward end portion of the part 3 is in the form of a projecting straight tube 4 which is connected with the transversely extending disk 5 which is provided at its upper or inner end with an annular screw threaded flange 6. The forward or outer end portion of the part 2 is tapered as indicated, while the upper or inner portion thereof is clamped fixedly to and around the annular screw threaded flange 6 of the part 3. The parts 2 and 3 taken together may be defined generally as the head of the brush. 65

7 designates a transversely extending disk 70 provided with a central forwardly and outwardly extending tube 8 which terminates in tapered walls 9 having a central opening 10. The inner surface of the tapered walls 9 form a valve seat for a purpose to be hereinafter described. The outer edge of the disk 7 is provided with a relatively wide flange-like portion, the portion 15 thereof adjacent the said disk being screw threaded, while the upper and more inward portion 80 thereof is flared as indicated at 16, and the said flared portion terminates in an annular cylindrical portion 17. At or about the point of connection between the flared portion 16 and the cylindrical portion 17, said 85 flange is crimped or pressed into engagement with the peripheral outer edge of a disk 20 to hold the latter permanently in the position shown in the drawing. The disk 20 is provided at its center with a 90

disk 20 is provided at its center with a square opening having a flange 21 surrounding the same, which projects forwardly or outwardly. The said disk 20 is provided with a plurality of openings 22. In the construction as shown, there are three of these openings arranged at the corners of a triangle, but it will be understood that there may be but one opening, or two or four or such number as may be desired and found to be practical. These openings are adapted to receive projections 23 upon a disk 24, said projections extending forwardly or outwardly. The said disk is rotatably mounted upon a tubular, interiorly threaded flange support 25, surrounding an opening at the center of a disk 26 (preferably of copper or other suitable, relatively hard metal) which disk is situated inside of and in con-

tact with the disk 24 and retains the latter in position. The portion of said disk 26 adjacent the said flange is bent inwardly or upwardly to form an annular space 27 between the disk 24 and the disk 26 for the purpose of holding a lubricant. The said disk 24 is provided with an upwardly or inwardly extending screw threaded flange 28 with which the inner or forward screw threaded end of a hollow cylindrical handle 29 is adapted to have detachable screw threaded engagement. The disk 26 is supported upon a discharge tube 30 of zinc or other suitable, relatively light material, which extends into a material containing reservoir or receptacle 31, also of zinc or other suitable relatively light material, situated inside of the handle 29. The discharge tube 30 is provided at its forward end with a laterally extending portion 32, which is followed by an enlarged cylindrical portion 33 which is externally screw threaded as shown. The internally screw threaded flange 25 is in engagement with the screw threads upon the cylindrical portion 33. At the forward or outer end of the portion 33 a flange is provided, from the outer edges of which an enlarged hollow portion 35 extends, the upper or inner portion of which is square in cross section as indicated, while the outer forward portion thereof is cylindrical, also as indicated, and terminates in an outwardly, reversely curved flange 36 which forms a seat for the forward end of a coiled spring 37, the said spring extending around the enlarged hollow portion 35 and its upper or inner end being seated against the disk 20, about the flange 21 thereof. The upper or inner end of the discharge tube 30 is pointed as shown at 39 and is provided with an opening or openings as 40 through which the material to be discharged from the reservoir 31 enters into the said tube. 41 designates a tube in alignment with and constituting a continuation of the discharge tube 30 and being in effect a part thereof. The upper or inner end of said tube is provided with an enlarged portion 42 which extends into the forward end part of the hollow portion 35 and is secured therein by soldering or otherwise. The forward end of the tube 41 is tapered as indicated at 43 and constitutes a valve for opening and closing the opening 10 in the forward end of the tube 8. Holes or openings 45 are provided at the forward end of the tube 41 through which the material escapes from the discharge tube 30—41, and thence through the opening 10 onto the brush 1.

It will be noted that the forward edge of the open end of the reservoir 31 is provided with a narrow, outwardly extending flange as indicated at 50, against the inner surface 65 of which the forward edge of the handle 29

contacts. It will be seen, therefore, that when the forward, screw threaded end of the handle 29 is screwed into the flange 28, it will clamp the forward, outer surface of said flange against the disk 24, so that the handle, 70 reservoir 31 and disk 24 will be caused to rotate as a unit in the operation of the device to expel liquid, semiliquid or plastic material from the reservoir.

Situated against the disk 7 and within the upwardly or inwardly extending flange thereof, is a washer 55 of suitable material, such as leather, the said washer being held in position by means of a disk 56 having an upwardly or inwardly extending flange 57, the said flanged disk being firmly pressed into position against the washer 55 and retained in position by reason of the friction between the flange 57 and the screw threaded portion 15 of the flange of the disk 7. The said disk 56 and washer 55 are provided with central openings through which the tube 41 extends. The surfaces or edges of these openings fit closely against the tube 41 and prevent the material being dispensed from working back from the openings 45 between the tube 41 and the tube 8 into the space occupied by the coiled spring 37 and the enlarged portion 35 having connection with and in effect constituting a part of the discharge tube 30.

In order to cause the discharge of the material from the reservoir 31 through the discharge tube 30, we have provided a piston, comprising a disk 60 having an opening at its center surrounded by an internally screw threaded flange 61. The said disk 60 is also provided with a flange 62 at its outer peripheral edge. These flanges extend forwardly; that is, toward the discharge end of the device. 63 designates a disk seated against the upper or inner surface of the disk 60. 64 designates a disk of thin material, such as zinc, which, at its outer edge, is provided with a flange which extends toward the rear or upper end of the handle. The said disk is provided at its center with an opening 66 corresponding with the openings through the disks 60 and 63. The said opening is formed through a 105 depressed portion of the said disk. Such depression forms a space between the central portion of the disk 64 and the disk 63 in which is seated or positioned a packing washer 68 of rubber or like material, the purpose of which is to prevent the liquid, semi-liquid or plastic material which may be contained in the upper closed end of the reservoir 31 from escaping through the openings in the disks 60, 63 and 64 around the 115 tube 30. The opening through the washer 68 is of less diameter than that of the discharge tube 30 and it is for that reason that the upper or rear end of the said tube is pointed as shown at 39. By so pointing the 120 125 tube 30, the opening through the washer 68 is of less diameter than that of the discharge tube 30 and it is for that reason that the upper or rear end of the said tube is pointed as shown at 39. By so pointing the 130

end of said tube it may be inserted readily through said opening.

The coiled spring 37 is in a compressed state and by reason of the fact that its forward end is seated against the flange 36, while its upper or inner end is seated against the disk 20, it tends to hold the discharge tube 30 in its forward position with the valve 43 seated against the inner surface of the wall 9, so as to close the opening 10. When in such position the projections 23 extend into the openings 22 in the disk 20 as shown in the drawing. When it is desired to cause the discharge of material from the reservoir 31 through the discharge tube 30, the handle 29, together with the disk 24 and the discharge tube 30—41, are pulled upwardly against the pressure or tension of the spring 37 so as to remove the projections 23 from the openings 22 and so as to open the valve 43. The handle, together with the disk 24, is then rotated toward the right. The flange 50 of the reservoir 31 being clamped between the forward edge of the handle 29, and the disk 24, it follows that the reservoir 31 also rotates in the same direction. The friction between the flanges 62 and 65 and the edge of the disk 63 and the inner surface of the reservoir 31 is such that the disks 60, 63 and 64 rotate with the reservoir and handle. Screw threads upon the discharge tube 30 and the flange 61 are so cut that rotation to the right causes upward or rearward movement of the piston toward the bottom or closed end of the reservoir 31. When the handle has been rotated through a partial revolution, the projections 23 are snapped or moved back into the openings 22 by the action of the spring 37, and if a greater quantity of material is desired, the said handle, discharged tube, etc., are again pulled outwardly or away from the discharge end of the device to remove the projections 23 from the openings 22, after which the said handle is rotated a further distance toward the right. The piston is thus gradually moved toward the closed end of the reservoir 31, so that ultimately the edge of the flange 65 contacts with the bottom or closed end of the said reservoir and in order to prevent the said flange from being forced up against the bottom of the reservoir the screw threads are omitted from a portion of the tube 30 as shown at 70, near the upper or rear end thereof. If the flange 65 were forced against the bottom of the reservoir the force of reaction might cause distortion of the disks 20 and 24 which are of thin material. This result should be avoided.

In order to prevent the creation of a vacuum in the space between the piston, comprising the parts 60, 63 and 64, and the disk 24, when the said piston is moved toward the bottom or rear end of the reservoir,

we have provided small vent openings 71, one of the said openings being in the bottom of the handle 29 while the other is in the side of the reservoir 31 at a point adjacent its upper end. 70

When the material has been discharged from a reservoir, it is discarded and a new reservoir containing the liquid or plastic material to be dispensed is inserted into the handle. It will be understood that when a new reservoir is substituted for one which has been discharged, the piston is situated at the forward open end thereof. In the construction as illustrated, the piston has been moved upwardly or inwardly a distance sufficient to have caused a discharge of practically half of the material originally contained in the reservoir 31. 75 80

It will be noted that the cylindrical portion 17 surrounds the screw threaded flange 28. The principal purpose of this arrangement is to provide for neatness of appearance. It will also be noted that the upper or inner end of the member 2 contacts with the flared portion 16. This arrangement 90 likewise is for the purpose of providing a neat and ornamental appearing structure or design. 95

We claim:

1. In a device for dispensing liquid, semi-95 liquid and plastic materials, the combination of a receptacle closed at one end and open at the other, the edges of the open end being provided with an outwardly extending flange, a discharge tube extending into said receptacle, a disk having a central flanged opening secured upon said discharge tube, a disk rotatably mounted on said flange and retained in position by said first named disk, the open end of said receptacle being seated 100 against said second named disk, which latter is provided with a screw threaded flange, and a hollow handle having an open end and the portion thereof adjacent said open end being screw threaded, said screw threaded 105 portion being adapted to be screwed into engagement with said screw threaded flange, and the edge of the open end of said handle being adapted to contact with the outwardly extending flange upon the said receptacle to clamp and hold the same against the said second named disk. 110 115

2. In a device for dispensing liquid, semi-120 liquid and plastic materials, the combination of a receptacle for the said materials, a discharge tube extending into said receptacle, said tube being provided outside of said receptacle with an enlarged portion, a disk having a flanged central opening which is detachably secured upon the said tube adjacent the enlarged portion thereof, a disk rotatably mounted upon the said flange and being situated intermediate the first named disk and the said enlargement, said second 125 named disk being provided with a threaded 130

flange, a hollow handle having an open end, the portion thereof adjacent said open end being screw threaded and adapted to have screw threaded engagement with the said 5 flange, and the said receptacle being situated inside of the said handle and having the edge of its upper end in contact with the said second named disk.

3. In a device for dispensing liquid, semi-
10 liquid and plastic materials, the combination
of a receptacle for the material, a threaded
discharge tube extending into said receptacle,
said discharge tube comprising an enlarged
portion situated outside of said receptacle,
15 a piston having threaded engagement
with said tube for forcing the material
from said receptacle through the said
discharge tube, a disk having a central
flanged opening, which disk is detachably
20 secured upon said tube adjacent said enlargement,
a disk rotatably mounted upon the
said flange intermediate the first named disk
and the said enlargement, and one of the
said disks being provided with a depression
25 whereby there is formed between the said
disks a lubricant holding chamber, the sec-
ond named disk having a screw threaded
flange, a hollow handle which incloses the
said receptacle, said handle having an open
30 end and the portion thereof adjacent the said
open end being threaded for engagement
with the screw threaded flange upon the sec-
ond named disk.

4. In a device for dispensing liquid, semi-
35 liquid and plastic materials, the combination
of a receptacle for containing the material
to be dispensed, a screw threaded tube ex-
tending into said receptacle and through
which the material is adapted to be dis-
40 charged, a piston situated in said receptacle
and having screw threaded engagement with
the said tube, and the said tube being pro-
vided with an enlarged hollow portion ex-
teriorly of the said receptacle, the forward
45 edge of said enlarged hollow portion ter-
minating in a lateral flange, a disk having a
central flanged opening, the said flange hav-
ing detachable engagement with the said
tube adjacent the enlarged portion thereof, a
50 disk rotatably mounted upon the said flange
and being retained by the first named disk
in position upon said flange, the said sec-
ond named disk being provided with a
threaded flange, a hollow handle having an
55 open end, the portion thereof adjacent such
end being threaded for engagement with the
said threaded flange, a second tube in aline-
ment with the first named tube, said sec-
ond tube having an enlarged inner end por-
60 tion which extends into the enlargement of
the first named tube and is secured therein,
a disk having a forwardly extending tube
having an opening in its forward end sur-
rounded by a valve seat, the said second
65 named tube extending into the last men-

tioned tube and its forward end being situ-
ated upon the said valve seat to close the said
opening, and the said third mentioned disk
being provided with a flange, packing ma-
terial situated in said flange and being fitted
70 against the external surface of said second
named tube, a disk permanently secured in
the flange of the third mentioned disk and
having an opening therein through which
the enlarged portion of the first named tube
75 extends, and a coiled spring situated inter-
mediate the last mentioned disk and the
flange upon the said last mentioned enlarged
portion, substantially as and for the purpose
described.

5. In a device for dispensing liquid, semi-
liquid and plastic materials, the combina-
tion of a receptacle for containing the ma-
terial to be dispensed, a discharge tube ex-
tending into said receptacle, means within
80 the said receptacle for causing the dis-
charge of the material therefrom through the said
tube, a disk having a central flanged open-
ing, the flange surrounding said opening
having detachable engagement with the said
tube, the said disk being provided with an
85 annular depression adjacent and surround-
ing the said central flange, a second disk
rotatably mounted upon the said flange, said
second disk being provided at its peripheral
edge with a threaded flange, a hollow handle
90 for inclosing said receptacle, said handle
having an open end and the part thereof ad-
jacent said open end being threaded to en-
gage the threads of the flange upon the
second named disk, substantially as de-
scribed.

6. In a device for dispensing liquid, semi-
liquid and plastic materials, the combina-
tion of a receptacle for containing the ma-
terial to be dispensed, a discharge tube ex-
tending into said receptacle, said tube having a
100 polygonal sided portion situated exteriorly
of the said receptacle, means situated within
the said receptacle and having movable en-
gagement with the said tube for causing a
discharge of material from the said recep-
tacle through the said tube, a hollow member
105 situated exteriorly of the said receptacle,
into and through which the said tube ex-
tends, a disk permanently secured in the said
hollow member and being provided at its
center with a polygonal sided opening in
110 which the polygonal sided portion of said
tube is situated and also being provided with
one or more openings therein situated inter-
mediate its center and its outer edge, a disk
having an opening at its center provided
115 with a flange which is detachably secured
to the said tube, another disk having an open-
ing at its center through which the said
central flange extends and on which said
disk is rotatable, and the said rotatable disk
120 being held in position by the disk secured
to said tube and the said rotatable disk being
125 to said tube and the said rotatable disk being
130

provided at its outer edge with a threaded flange, and said rotatable disk also being provided with one or more outwardly projecting lugs adapted to engage the opening or openings in the first named disk, a hollow handle having an open end, the portion thereof adjacent such open end being threaded to engage the threaded flange of the said rotatable disk, means for effecting movement of the means within the receptacle longitudinally of the said tube to cause the discharge of material from the said receptacle through said tube, and yielding means for holding the said projection or

10 projections upon the said rotatable disk in detachable engagement with the opening or openings in the first named disk.

7. A device for dispensing liquid, semi-liquid and plastic materials comprising a receptacle for containing the material to be discharged having an open end, a discharge tube extending into said receptacle, a disk having a flanged opening at its center, the said flange having detachable connection 20 with the said discharge tube, a second disk for closing the open end of said receptacle having operative connection therewith, said second disk being rotatably mounted upon the central flange of the first named disk,

means for retaining the said second named disk on the flange surrounding the central opening of the first named disk, and means for causing the discharge of the material from the said receptacle when it is rotated in a predetermined direction.

8. In a device of the character described, the combination of a receptacle closed at one end and open at the other, the edges of the open end being provided with an outwardly extending flange, a discharge tube 40 extending into said receptacle, a disk rotatably supported on the said discharge tube, said disk being adapted to close the open end of said receptacle, a hollow handle having an open end, means whereby the said open end is adapted to be secured to the said disk, and the open end of said handle being adapted to contact with the outwardly extending flange upon the said receptacle to clamp and hold the same against the said 45 disk.

In testimony that we claim the foregoing as our invention, we have hereunto signed our names this 31st day of March, A. D., 1920.

WILLIAM WILSON HEINITSH.
ISAAC C. SHALKOP.
ALEXANDER B. LAUTERBACH.
